HENRY A. EILERS, OF INDIANAPOLIS, INDIANA, ASSIGNOR TO THE HORNBROOK-PRICE CO., OF INDIANAPOLIS, INDIANA, A CORPORATION OF INDIANA.

METALLIC DRINKING-TROUGH.

1,160,498.

Specification of Letters Patent. Patented Nov. 16, 1915.

Application filed March 17, 1913. Serial No. 754,849.

To all whom it may concern:

Be it known that I, HENRY A. EILERS, a citizen of the United States, residing at Indianapolis, in the county of Marion and 5 State of Indiana, have invented a new and useful Metallic Drinking-Trough, of which the following is a specification, reference being had to the accompanying drawings, and to the letters and figures of reference 10 marked thereon.

This invention relates to a drinking trough for cattle, swine and fowls and for horses or other animals, the invention having reference more particularly to a drinking trough of light weight that is suitable 15 for shipment at low rates from factories.

An object of the invention is to provide a drinking trough that shall be so constructed that it may be readily cleansed, while 20 fixedly secured in normal position, for hygienic reasons.

A further object is to provide a light weight metallic drinking trough that may be constructed at relatively small cost and 25 be free from sharp edges that might cause injury to the live stock when drinking.

A still further object is to provide a metallic drinking trough that shall be so constructed as to be easily moved to position and 30 be firm and strong, and which may be readily secured firmly in the required position and be durable and economical in use.

With the above mentioned and other objects in view, the invention consists in a 35 metallic drinking trough comprising various novel features, and in the parts and combinations and arrangements of parts, as hereinafter particularly described and claimed.

Referring to the drawings, Figure 1 is a 40 side elevation of the improved trough; Fig. 2, a top plan thereof partially broken away; Fig. 3, a fragmentary bottom plan; Fig. 4, an end elevation; Fig. 5, a transverse section on an enlarged scale on the line A A in Fig. 1; Fig. 6, a fragmentary side elevation on an 45 enlarged scale; and Fig. 7, a fragmentary longitudinal section on the plane of the line B B in Fig. 5.

Similar reference characters in the different figures of the drawings indicate like 50 parts or features of construction herein referred to.

In practically carrying out the objects of 55 the invention a body or main portion 1 is

formed of sheet metal rolled so as to be approximately U-shaped in cross-section and corresponding approximately to one-half of a hollow cylinder divided longitudinally, and two outwardly extending joint flanges 60 2 and 3 are formed on the two opposite ends of the body portion. Two identically shaped end portions 4 and 5 are formed of sheet metal and pressed to shape so that each is a quarter segment of a hollow globe, and the 65 end portions have joint flanges 6 and 7 formed thereon that correspond with the flanges 2 and 3 and therewith form joints 8 and 9 respectively on vertical planes. Two semi-circular clamp or collar plates 10 and 70 11, suitably perforated to receive rivets, are placed against the flanges 2 and 6 respectively, two similar plates 12 and 13 being placed against the flanges 3 and 7 respectively. The plates 10 and 11 are firmly 75 secured to the flanges 2 and 6 and the flanges secured together by means of rivets 14 and 14' arranged somewhat below the plane of the top of the trough, the plates 12 and 13 being secured to the flanges 3 and 7 and the 80 flanges secured together by means of rivets 15 and 15'. The clamp plates serve to stiffen the trough and insure reliable joints, and being composed of bent flat bar iron have blunt edges which guard the relatively thinner 85 and sharper edges of the flanges so that the flanges do not protrude and menace the live stock.

The top of the trough is provided with a substantial rim or molding that covers the 90 upper edge of the body and end portions of the trough and thoroughly stiffens the upper portion of the trough, said rim being composed of two U-shaped pieces of L-section angle iron of equal length, one piece being 95 bent at its middle portion so as to form a semi-circular plate 16 that is placed against the inner side of the end portion 4, and two straight side plates 17 and 18 extending along the inner side of the body portion 1 100 to the plane of the middle thereof, the rim having a curved flange portion 19 extending horizontally outward over the top of the end portion 4, and side portions 20 and 21 extending outwardly over the top of the opposite side portions of the middle portion 1. The remaining piece of angle iron is likewise bent at its middle portion to form a semi-circular portion 22 that is placed 105 against the inner side of the end portion 5, 110

and two straight side plates 23 and 24 extending along the inner side of opposite portions of the body portion 1 to the ends of the plates 17 and 18 respectively, the rim portion having a curved flange portion 25 extending outward over the top of the end portion 5 and flanges 26 and 27 extending over the top edges of the body portion to the ends of the flanges 20 and 21 respectively. 5
10 The rim portion 16 is secured to the end portion 4 by means of rivets 28 and the plates 17 and 18 are secured to the body portion 1 by rivets 28', the end portions of the plates 17 and 18 being secured to the body portion 15 by rivets 29. The rim portion 22 is secured to the end portion 5 by rivets 30 and the plates 23 and 24 are secured to the body portion by rivets 30', the end portions of the plates being secured by rivets 29'. The joints 20 8 and 9 are rendered water tight by means of solder 31 and 31' respectively.

In order to prevent the animals from crowding over against others while drinking and to thoroughly stiffen the upper portions 25 of the sides of the trough, a flat bar 32 is placed transversely upon the top of the rim with one end covering the joint of the flanges 20 and 26 and is secured to the flanges by rivets 33 and 33', the opposite 30 end portion of the bar being secured to the end portions of the flanges 21 and 27 by rivets 34 and 34'. Preferably other cross bars 35 and 36 are arranged on opposite sides of the bar 32 at a suitable distance 35 therefrom, and similar bars 37 and 38 suitably spaced between the bars 35 and 36 and the adjacent end portions 19 and 25 respectively, the cross bars being relatively narrower than the middle bar 32 and are secured to the flange portion of the rim by 40 means of rivets 39 and 39' in opposite ends thereof.

Two base plates 40 and 41 are provided that have upturned flanges 42 and 43, each 45 base plate being composed of L-section angle iron, and the middle portion of the flange 42 is secured to the clamp plates 10 and 11 at the middle or under portion thereof by means of a rivet 44, the clamp plates resting 50 upon the base plate 40. The flange 43 is similarly secured to the clamp plates 12 and 13 by a rivet 45, the clamp plates resting upon the base plate 41.

In order to prevent the trough from turning over on the base plates, two legs 46 and 47 are secured at their upper ends by 55 means of rivets 48 and 49 to the upper portions of the clamp plates 10 and 11 and extend downward to the base plate 40, being 60 slightly offset so as to stand against the outer side of the flange 42, two similar legs 50 and 51 being secured at their upper ends by rivets 52 and 53 to the upper portions of the clamp plates 12 and 13 and extending 65 downward to the base plate 41 on the outer

side of the flange 43. Preferably two braces 54 and 55 are connected at their upper ends with two of the rivets 28 so as to be secured to the rim portions 17 and 18 respectively and extend downward to the inner side of the flange 42, and the lower ends of the braces and the lower ends of the legs 46 and 47 are secured to the end portions of the flange 42 by means of rivets 56 and 57. Two similar braces 58 and 59 are connected 70 by rivets 28' to the body portion 1 in proximity to the opposite end thereof and extend downwardly at an oblique angle to the inner side of the flange 43, the lower ends of the braces and the lower portions of the legs 50 and 51 being secured to the end portions of the flange 43 by means of rivets 60 and 61 respectively. In order to secure the trough to a suitable foundation or blocks by means of screws or spikes, the end portions 75 of the base plate 40 are provided respectively with openings 62 and 63, the end portions of the base plate 41 being likewise provided with openings 64 and 65.

In practical use the trough is supplied 80 with water by any suitable means or source and after being used as is customary, the trough is periodically cleansed by scrubbing it and mopping out so as to be thoroughly cleansed, and as will be obvious, the foundation upon which it is supported may be 85 adapted to be turned so as to drain water from the trough, or the trough may be disconnected from the foundation and turned over as may be desired.

Having thus described the invention, what 90 is claimed as new is—

1. A drinking trough comprising a semi-cylindrical main portion, end portions fixedly secured to opposite ends respectively 105 of the main portion, each end portion being approximately a quarter-section of a hollow globe in contour, two base members connected to the main portion near the ends thereof, a plurality of legs secured each 110 to an end portion of a base member and also to the main portion adjacent an end of the top thereof, a rim extending along the top of the main portion and the end portions and secured thereto, a plurality of transverse bars secured to the top of the rim, and a plurality of braces secured each to an end portion of a base member and to the lower portion of a leg and also to the main portion of the trough adjacent the rim at a distance from the upper portion of the leg.

2. A drinking trough comprising a semi-cylindrical main portion having flanged ends, two globular-segmental end portions having flanges thereon arranged respectively 125 against the flanges of the main portion and secured thereto, a rim composed of two identically shaped members abutting one against the other midway between the ends of the main portion a portion of the rim extending 130

along the inner side of the main and end portions, another portion of the rim extending outward over the top of the main and end portions, and a transverse bar secured at its ends to the abutting portions of the two rim members.

3. A drinking trough comprising a semi-cylindrical main portion having flanged ends, two globular-segmental end portions 10 having flanges secured respectively to the flanges of the main portion, a rim comprising a plate extending along the inner side of the main and end portions and a flange extending outward over the top of the main 15 and end portions, a plurality of cross bars secured upon the rim to the flange thereof, two base plates having each an upturned

flange and also an opening in each end portion thereof to receive a securing device, the middle portion of the flange of each base plate being secured to the flange of an end of the main portion and also to the flange of the adjacent end portion, and a plurality of legs secured each to an end portion of the base plate flange and also to an upper portion of the adjacent flanges of the main and end portions. 20 25

In testimony whereof, I affix my signature in presence of two witnesses.

HENRY A. EILERS.
